UNITED STATES PATENT OFFICE.

ULYSSES G. ROBINSON, OF BELGRADE, NEBRASKA.

CALCULATING-MACHINE.

1,118,950.

Specification of Letters Patent.

Patented Dec. 1, 1914.

Application filed April 27, 1912. Serial No. 633,699.

To all whom it may concern:

Be it known that I, ULYSSES G. ROBINSON, a citizen of the United States, residing at Belgrade, in the county of Nance and State of Nebraska, have invented a new and useful Calculating-Machine, of which the following is a specification.

One object of the present invention is to provide, in a calculating machine, novel means for maintaining the record web taut, so that the web may be driven readily by an actuating roller, the web being held in proper condition to coöperate with an indicator.

15 A further object of the invention is to provide a calculating machine from which the record-holding elements and the indicators may be removed readily, permitting the machine to be used for calculations of different sorts.

With the foregoing and other objects in view, which will appear as the description proceeds, the invention resides in the combination and arrangement of parts and in 25 the details of construction hereinafter described and claimed, it being understood that changes in the precise embodiment of invention herein disclosed can be made within the scope of what is claimed without departing from the spirit of the invention.

In the drawings.—Figure 1 is a perspective; Fig. 2 is a transverse section; Fig. 3 is a longitudinal section, the cutting plane passing between the constituent parts of 35 the case; and Fig. 4 is a fragmental end elevation of the case.

In carrying out the invention there is provided a case 1, comprising a back 2 and a front 3, the parts 2 and 3 being of box-like 40 construction. The rear wall of the back 2 is indicated at 4, and is preferably imperforate, there being an opening 5 in the front wall of the part 3 of the case. Across the opening 5 extends a transparent plate 6.

45 The part 2 of the case 1 may be provided with a handle 7, the parts 2 and 3 being united in their lowermost portions by hinges 8.

The parts 2 and 3 of the case 1 may be 50 equipped with supporting strips 9, to afford a firm base.

Any suitable locking means may be provided for holding the parts 2 and 3 of the case together. In the present instance, a 55 hook 10 is pivoted to the back 2 and is

adapted to coöperate with an eye 11 carried by the front 3.

In both of the end walls 12 of the parts 2 and 3 of the case 1 there are mating notches, one set of notches 14 being of semi-circular 60 form, to define a circular opening 15. The other set of notches are of elongated form, as indicated at 16, to define an elongated opening 17.

The invention includes a primary roller 65 35, provided with trunnions 18 at its ends, which trunnions 18 are journaled in the openings 15 formed by mating notches 14. The trunnions 18 terminate in knobs 19, located outside of the case 1 and constituting means whereby the primary roller 35 may be rotated, the knobs 19 constituting means for preventing the primary roller 35 from moving endwise within the case 1. The invention further includes a secondary 70 roller 20 provided at its ends with trunnions 22, received in the openings 17 defined by the registering notches 16. The trunnions 22 are held for rotation in the openings 17, the construction, however, being such that the trunnions may move transversely in the openings 17, thus permitting the secondary roller 20 to have transverse movement.

An endless, record web 23 is trained 85 about the rollers 35 and 20. The web 23 is supported by the primary roller 35 and in its turn constitutes a means for supporting the secondary roller 20. The secondary roller 20 acts gravitationally to maintain 90 the web 23 taut, so that the web may be actuated readily by the primary roller 35 when the said roller is rotated through the medium of the knobs 19.

A pair of indicators 24 and 25 extend 95 across the opening 5 and since the web 23 is maintained taut by the gravitational action of the secondary roller 20, the web at all times is in position to coöperate with the indicators 24 and 25. There are openings 100 26 in the end walls 12 of the case 1, through which openings the indicators 24 and 25 may be inserted, both ends of the indicators being thus supported by the case 1. One end of the case 1 may be equipped with set 105 screws 27, adapted to engage the indicators 24 and 25 to hold the same against longitudinal movement.

The record web 23 may be inscribed in any suitable manner and the indicators 24 110

and 25 may be inscribed to coöperate with the web. It has been presupposed in the present instance that the device is to be used by a lumber dealer, and with this end in view, two tables are inscribed upon the web 23, one of which tables is adapted to be employed for indicating the number of board feet in a stick of timber of given dimensions. This table includes a central vertical column of figures indicated at 28, which figures serve to indicate the number of pieces of timber. Parallel to the column of figures indicated at 28 are other columns of figures indicated at 29, these columns of figures shown at 29 serving to indicate the number of board feet in a stick of timber the length and the transverse dimensions of which are known. The transverse dimensions of the stick of timber are indicated, as set forth at 30, upon the member 24, and the length at 31. When the web 23 coöperates with the indicator 24 it is possible to read off at a glance, the number of board feet in a stick of timber having a given length and a given cross sectional area. Referring to the upper part of Fig. 1 it will be observed that the operator is informed at a glance that twenty-four sticks of timber 2 by 10 and sixteen feet long contain six-hundred and forty-board feet.

The device may be used also to indicate the price of a given quantity of lumber at a given price per thousand board feet. With this end in view, another table is inscribed upon the web 23, which table appears in the lower portion of Fig. 1. The table under consideration comprises a central vertical column of figures indicated at 32, this column setting forth the number of board feet. Parallel to the column 32 are other columns indicating the values of fixed numbers of board feet at fixed prices per thousand feet. Upon the indicator 25 may be inscribed the prices per thousand feet, as indicated at 34. Referring to the table shown in the lower portion of Fig. 1 it will be seen, for instance, that three board feet listing at thirty-five dollars a thousand will 50 cost ten cents.

The tables above mentioned are extremely simple and further detailed description of their operation is unnecessary.

Recalling that the device herein disclosed may be provided with webs 23 having graduations different from those shown, it is obvious that the indicators 24 and 25 must be removable, readily, and that it must be possible to substitute one web for another. Attention is therefore directed to the fact that by loosening the set screws 27,

one set of indicators 24-25 may be slipped out of the case 1, another set of indicators being mounted in the place of those removed. Moreover, by loosening the locking device 10-11, the constituent parts 2 and 3 of the case may be spread apart, whereupon the rollers 35 and 17 may be removed, permitting the insertion of another web 23. The indicators 24 and 25 are longitudinally adjustable, and are adjustable transversely of the direction of travel of the web 23, and consequently, by manipulating the set screws 27, the graduations upon the indicators may be made to correspond to the graduations upon the web.

The web 23 is actuated by rotating the primary roller 35 through the medium of the knobs 19. Since the web 23 serves as the sole means for supporting the secondary roller 20 for vertical movement, the web is at all times maintained taut by the gravitational action of the secondary roller. The web 23 will, therefore, grip the primary roller 35 to such an extent that the web will travel readily when the primary roller is actuated. Furthermore, owing to the fact that the web is maintained taut by the action of the secondary roller 17, the web will be held close to the indicators 24 and 25.

The device herein disclosed is of few parts, and may be fashioned at trifling expense.

It is obvious that the dimensions of the structure may be increased greatly, thereby permitting the solution of a wide variety of problems.

Having thus described the invention, what is claimed is:—

A device of the class described, comprising an upper cylindrical roll, means for revolubly supporting the same, a lower cylindrical roll constructed to rotate and shift in a plane extending through the axes of the said rolls, an endless web trained around the said cylindrical rolls and provided with tabulations thereon, a pair of indicating rods lying in a plane tangential to the surface of both of said cylindrical rolls, the said indicating rods extending substantially parallel and adjacent to the line of tangency of the said plane as defined by the web with the said peripheral surfaces of the rolls.

In testimony that I claim the foregoing as my own, I have hereto affixed my signature in the presence of two witnesses.

ULYSSES G. ROBINSON.
